UNITED STATES PATENT OFFICE

2,553,920

WIRE TOOL

Fritz Johnson, Idaho Falls, Idaho

Application August 14, 1947, Serial No. 768,599

2 Claims. (Cl. 254—80)

1

This invention relates to pliers.

An object of this invention is to provide a pair of pliers designed particularly for tightly pulling, stretching, gripping and cutting wire ties used in concrete forms or the like.

Another object of this invention is to provide in a pair of pliers, a lever arm fixed to end extending laterally and forwardly from one of the jaws which is adapted to bear against a stationary part with the outer end of the lever forming a fulcrum point so that the lever may be rocked with the pliers and thereby effect a tightening of the wire or other article gripped between the jaws of the pliers.

A further object of this invention is to provide in a pair of pliers an improved jaw construction wherein one of jaws is formed as a cutter which is so constructed that the wire or other article gripped between the jaws will not be completely cut through until excess pressure is placed on the handles.

With the above and other objects in view, my invention consists in the arrangement, combination and details of construction disclosed in the drawings and specification, and then more particularly pointed out in the appended claims.

In the drawing,

Figure 1 is a detail side elevation of a pair of pliers constructed according to an embodiment of this invention,

Figure 2 is a fragmentary sectional view taken on the line 2—2 of Figure 1,

Figure 3 is a sectional view taken on the line 3—3 of Figure 1.

Referring to the drawing, the numerals 10 and 11 designate generally a pair of handles which are pivotally connected together, being mounted on a pivot 12 which extends through the bifurcated forward end 13 of the handle 10 and through an obtusely disposed extension 14 formed on the forward end of the handle 11.

The bifurcated portions 13 of the handle 10 extend on an obtuse angle to the length of the handle 10 and a combined clamping and cutting jaw 15 is carried by the forward ends of the bifurcations 13.

The jaw 15 includes an insert 16 comprising a combined gripping and cutting member which is formed with a V-shaped inner face 17 confronting an insert 18 carried by a jaw 19 which is fixed to the obtuse extension 14.

A laterally and forwardly projecting lever arm 20 is formed integral with the extension 14, projecting forwardly and laterally from the jaw 19 and formed at its terminal end with a head 21.

2

The head 21 is adapted to engage a fixed support and constitutes a fulcrum by means of which the pliers are adapted to be rocked upwardly so as to form sufficient leverage to tighten a pair of wire strands 22 which are gripped between the inserts 16 and 18 of the jaws 15 and 19 respectively.

The wire 22 may be a tie wire which is used in concrete forms for holding the opposite sides of the forms against spreading. After the wire 22 has been pulled tightly by rocking of the pliers on the head 21, the wire may be twisted and this wire may then be cut off by exerting additional pressure on the handles 10 and 11, the insert 16 cutting through the wire strand or strands which are gripped between the two jaws.

In the use and operation of these pliers, the wire 22 is initially gripped between the jaws 15 and 19 with the jaws positioned closely adjacent the face of the work, as shown in full lines in Figure 1. With the wire or wire strands gripped between the jaws, the handles 10 and 11 may then be rocked upwardly to substantially the dotted line position shown in Figure 1, the rocking of the pliers being effected by engagement of the head 21 against a stationary support.

After the wire 22 has been tightened and twisted the wire may be cut by application of additional pressure on the handles 10 and 11. Through the provision of the inserts 16 and 18, the gripping faces of the jaws may be formed of hardened steel wires, the remaining portions of the pliers may be formed out of forged steel or the like.

The use of these pliers will permit the rapid mounting of tie wires in concrete forms and the rapid tightening or tensioning of the wires without the use of additional tools.

I do not mean to confine myself to the exact details of construction herein disclosed, but claim all variations falling within the purview of the appended claims.

What I claim is:

1. A pliers comprising a pair of handles, one of said handles being formed with a bifurcated end, the adjacent end of the other of said handles extending through said bifurcated end, a pivot member extending through said pair of handles, a laterally extending elongated jaw carried by said bifurcated end, a confronting jaw carried by said other handle and engageable with said first mentioned jaw, and a lever arm extending forwardly of said first mentioned jaw and integral with said other handle.
2. A pliers comprising a pair of elongated handles, one of said handles being formed with a

bifurcated end, said handles being crossed with the other of said handles extending between the bifurcations of said one handle, pivot means extending through said bifurcations and said other handle, a pair of laterally extending confronting bars carried by said bifurcations and said other handle and spaced longitudinally from said pivot means, one of said bars having a rounded face, the other of said bars being formed with a wedge shaped face, a lever arm extending forwardly of the bar on said other handle, and a head on said lever arm perpendicular to the length thereof and constituting a fulcrum for said pliers.

FRITZ JOHNSON.
